UNITED STATES PATENT OFFICE.

ARTHUR A. MERRITT, OF EDGEWOOD, RHODE ISLAND, AND JOHN F. GETLER, OF NEW HARTFORD, NEW YORK, ASSIGNEES TO WILLCOX & GIBBS SEWING MACHINE CO., OF NEW YORK, N. Y., A CORPORATION OF NEW YORK.

SEWING-MACHINE PRESSER FOOT.

Application filed August 3, 1918, Serial No. 248,139. Renewed January 25, 1926.

The present invention relates to presser-feet for sewing machines. Although designed especially for use with what is known commercially as the Willcox & Gibbs Sewing Machine Company's "Flatlock machine"—shown for example in patents to Stockton Borton 1,041,574, and to A. A. Merritt 1,041,652, both dated October 15th, 1912, and producing the seam of Borton Patent 10 883,614, dated March 31st, 1908—this invention is not restricted to use with any particular type or make of sewing machine.

The principal object attained by this invention is the provision of a sewing-machine presser-foot capable of affording approximately equal feed control and uniform advance of the work at both sides of a seam when a certain thickness of material or fabric (either one or more layers) at one 20 edge is to be joined to a different thickness (either one or more layers) at the other edge of the seam. A further object is to provide a presser-foot capable of so functioning regardless of the position of the greater thickness of material at one or the other edge of the seam and of its use upon like thicknesses of material at both edges of the seam. Another object is to provide means, preferably in the form of one or more attachments, 30 capable of being applied to presser-foot structures already in use or known, to give the same the capacity of functioning in the manner above indicated. Incidental to the attainment of the foregoing objects, there is 35 attained the further object of providing parts which may be cheaply replaced to overcome defects from wear caused by the action of the feed means. Still other objects are attained as will appear from the detailed description which follows.

The novel features of invention will be more fully explained with reference to the accompanying drawing illustrating what is now believed to be the preferred embodiment 45 of the invention in a presser-foot especially intended for use on a machine of the character of the aforesaid Flatlock machine. In said drawing—

Fig. 1 is a perspective view of the presser foot, with the trimmings deflector partly broken away.

Fig. 2 is a front view in which part of the presser-foot and part of the arm which carries the movable trimmer blade are shown in elevation, and in which the work-plate, feed-member, and part of the work-arm supporting the work-plate, are shown in transverse section. Two thicknesses of fabric under one side of the presser-foot are to be joined to a single thickness of fabric under 55 the other side thereof.

Fig. 3 is a side elevation from the left of Fig. 2, with the two thicknesses of fabric in section.

Fig. 4 is a side elevation from the right 65 of Fig. 2, with the single thickness of fabric in section and the movable trimmer-blade and its actuating arm omitted.

Fig. 5 is a detail perspective of one of the 70 spring bottoms of the presser-foot.

Fig. 6 is a bottom view of the work contacting parts of the presser-foot, with dotted line positions of the spring bottoms showing the adaptability thereof to be spread apart and widen the slot between said spring bottoms to pass abnormal thickness of material, 75 as in the case of a cross seam.

Fig. 7 is a detail view illustrating stop means to limit the spread of the spring bottoms at their rear ends.

Fig. 8 is a detail of the trimmings-deflector.

In many particulars the presser-foot herein illustrated is substantially that of Figs. 46 and 47 of the aforesaid Merritt Patent 85 No. 1,041,652. 30 is the main body of the foot having a split hub 31 adapted to be securely clamped to the lower end of a presser-foot bar movable in the head of the machine, a portion of the wall of which is 90 shown at 80 in Fig. 1. The usual spring 81, the tension of which may be adjusted by a nut 82, yieldingly presses the foot against the work while permitting vertical vibration thereof in response to upward movements of the feed. A cross-thread carrier 32, a cross-thread hook 33, driving connections therefor, and the mounting of these parts on the foot-body 30, are substantially 95 the same as in the said Figs. 46 and 47 of 100 said Merritt patent. Thus, said hook 33 is removably secured by a set-screw to the

lower end of an upright shaft 34, Fig. 1, rotatable in an extension 35 of the foot-body 30. A rock-lever 36 (Fig. 1) secured to the upper end of shaft 34 has a long arm and a short arm, the latter connected by link 37 to a driving part not shown in the drawing. The long arm extends in a curve to a pivotal connection with one end of a link 38, the other end of said link being in turn pivotally connected to crank-arm 39 at the upper end of a shaft 40 journaled in an upright opening in the foot body. Cross-thread carrier 32 is detachably secured to the lower end of shaft 40. The cross-thread hook 33 and carrier 32 operate in the manner set forth in the patents aforesaid.

The horizontally disposed flattened portion of the foot-body 30, which extends forward of what constitutes the shank of the foot is notched, forming two toes or branches 41, 42 (Fig. 1) between which the upturned edges of the fabric advance and are trimmed by the trimmer-blade. Fixed trimmer-blade 43 is secured in a horizontal opening through toe 42 by a clamp-block 44 and screw 45 (Figs. 1 and 2). Movable trimmer-blade 46 works in a horizontal opening through toe 41 and is clamped to the lower end of the trimmer-arm 47, Fig. 1, which is the same in construction and operation as arm 643 of Fig. 47 of the aforesaid Merritt Patent 1,041,652, the construction being such that the upper movable blade 46 bears upon the upper surface of fixed blade 43 and, with its arm 47, participates in any upward movement of the presser-foot and of blade 43. To deflect to one side the trimmings removed by the trimmer-blades, a deflector 48 is pivoted by a screw 49 to toe 41. It may be swung outward on said pivot-screw, from its normal position shown in Fig. 1, to give access to the thread manipulating elements.

50 (Figs. 1 and 6) is a needle-opening through the presser-foot. 51 (Figs. 6 and 7) is a chaining-foot positioned in an opening through the foot to the rear of said needle-opening, the same as shown in the patents aforesaid. A stem 52 on said chaining-foot 51 projects upward into a socket of the foot body 30, and is acted upon by a spring 53 (Fig. 7) to yieldingly hold the chaining-foot to its work. A screw 54 threaded into stem 52 with its head movable in a slot in the wall of 30 limits the movement of the chaining-foot relative to the main foot. Any suitable feed may be used, either single or double, such as shown in the patents aforesaid. Fig. 2 shows a feed member 55 working through cloth-plate 56 (also shown in Figs. 3 and 4) supported by a work-arm 57.

The structure as thus far described in detail is substantially that of the patents aforesaid, and for all ordinary uses of sewing machines such as the aforesaid Flatlock machine, constitutes a complete presser-foot

of the highest efficiency. But, in operations upon fabric of materially different thicknesses under opposite sides of the foot—as where the edge of a single thickness of heavy fabric is to be joined to the edge of a double thickness of the same fabric—the lifting of the foot by the greater thickness of material under one side thereof interferes with the satisfactory engagement of the foot with the lesser thickness of material under the other side thereof, and consequently with the feed of the material or fabric by the feed-means. The means of the present invention efficiently meet such conditions, and may be in the form of an attachment, or attachments, 80 removably applicable to a presser-foot, such as hereinbefore described, and which without such spring members is suitable for use with material of approximately uniform thickness under both sides of the foot.

60 is a foot bottom extending beneath the left-hand side of the foot proper lengthwise thereof. It is made of a flat strip of spring metal, preferably steel, slightly bowed along its middle and bent over at its opposite ends, similar to the runner of a boy's sled. The forward bent end 61 fits toe 42 of the foot and is secured thereto by a screw 62. The hooked rear end of bottom 60 engages about the rear edge of the foot proper forming a loose connection thereto allowing freedom of longitudinal movement, as the bowed bottom is flattened more or less against the normal bottom surface of the foot proper, and also freedom of lateral movement under conditions presently described. In addition to thus providing for attachment of the flat-spring bottom member to the foot proper, the rounded surfaces formed by the bending of the spring at both ends avoid angular edges to be passed by the material in its advance under the foot.

70 is a similar foot bottom extending beneath the right-hand side of the foot proper lengthwise thereof, secured at its forward bent end 71 to toe 41 by a screw 72, and at its rear hooked end 73 making loose connection to the rear edge of the foot proper, affording freedom of longitudinal and lateral movement relative thereto. The inner edges of the two flat-spring bottom members are so relatively shaped as to fit about the chaining-foot 51 and clear the needle-opening 50, said edges standing closest together at 64 and 74 just in front of said needle-opening, from whence they gradually diverge to their forward ends. Thus the inner edge of each member, from approximately the front end of the member back to the needle opening 50, is inclined at an angle toward the vertical median longitudinal plane of the presser-foot. Furthermore, the inner edges of said members between the opposing portions 64 and 74 and the bottom surface of the main body 30 of the presser-foot, form a shallow

groove along the bottom of the presser-foot extending from the rear end of the slot back to the needle opening 50. The upstanding trimmed fabric edges are crowded and compacted together in this groove as they pass under the presser-foot back to the needle opening. As also appears, there is an offset, or approximately right angle shoulder, in the inner edge of each flat spring-bottom member just in advance of the needle opening. Abnormal thickness of material—for example, where there is a cross-seam lateral to the seam being formed—passing between the inner edges of the flat-spring bottom members, particularly the parts 64 and 74 thereof, is accommodated and passed by lateral yielding and spreading, such as illustrated by dotted line positions Fig. 6, of said bottom members. As soon as the abnormal thickness of material passes the members spring back to their normal positions shown in full lines, Fig. 6. Such spreading may be limited, if desired, by any suitable means, for example the rod 86 hooked at both ends 25 to engage hooks 63 and 73 respectively of the flat-spring bottom members, as clearly shown in Fig. 7.

As shown in Figs. 2, 3 and 4, the presser-foot is operating upon two thicknesses of material or fabric under the left-hand side thereof to be joined to a single thickness of material under the right-hand side thereof. The spring pressure exerted by the regular presser-foot spring 81, being more powerful than the spring power of either, or both, spring bottoms 60 and 70, flat-spring bottom 60 in engagement with the double thickness of material is flattened firmly into contact with the surface of the foot proper. At the same time the flat-spring bottom 70, still bowed outward from the bottom of the foot proper, as shown in Fig. 4, makes firm yielding engagement with the single thickness of material under the right-hand side of the foot. The material so held is uniformly advanced under both sides of the foot by the feed (see feed-member 55 of Fig. 2 for example) notwithstanding the different thicknesses. Obviously, if the two thicknesses of material were under the right-hand side of the foot and the single thickness under the left-hand side, the action of the flat-spring bottom members would be reversed. In thus automatically accommodating itself to differences and variations in thickness of material, the presser-foot is enabled to maintain a firm and distributed pressure upon the work against the cloth-plate and feed members, and to afford an even feed at both sides of the seam regardless of differences and variations in the thickness of material. If a lesser thickness of material is to be regularly fed under the same side of the foot, the flat-spring bottom member may be omitted at that side. But to make the foot universally

applicable regardless of differences of thickness, and of which side of the foot is to engage the greater thickness, it is preferable to employ the flat-spring bottom members at both sides of the foot.

In addition to their main functioning above set forth in the detailed description, the bottom members 60 and 70 serve to take the wear of the cooperating feed member or members, particularly wear caused by the teeth thereof. When worn to an extent to become defective, said bottoms can be cheaply replaced without the loss of an entire foot and of expensive repairs thereto.

What is claimed is:

1. A sewing machine presser-foot having two flat-spring bottom members acting to independently yieldingly engage work thereunder at opposite sides respectively of a median vertical plane extending longitudinally of the foot.

2. A sewing machine presser-foot having two flat-spring bottom members at opposite sides thereof respectively, and acting to independently yieldingly engage work thereunder.

3. A sewing machine presser-foot notched at its forward end with portions of the foot lying on both sides of said notch and having two flat-spring bottom members extending along the foot at opposite sides respectively of said notch and acting to independently yieldingly engage work thereunder.

4. A sewing machine presser-foot having two work contacting bottom members movable one relatively to the other in a lateral direction to permit the passage of material between the opposing edges thereof.

5. A sewing machine presser-foot having two work contacting bottom members separated by an intervening space and mounted on the foot to yieldingly spread apart one relatively to the other in a lateral direction to increase the intervening space.

6. A sewing machine presser-foot having on its bottom two work contacting members separated by an intervening space longitudinally of the foot and adapted to be spread further apart one relatively to the other in a lateral direction by the passage of material between the inner edges thereof.

7. A sewing machine presser-foot having on its bottom two flat-spring members acting to independently yieldingly engage work thereunder, said members being separated by an intervening space longitudinally of the foot and adapted to yieldingly spread further apart one relatively to the other in a lateral direction by the passage of material between the inner edges thereof.

8. A sewing machine presser-foot having a flat-spring bottom member secured at one end to the foot-body and at its other end having a loose connection to said foot-body.

9. A sewing machine presser-foot having

- a flat-spring bottom member extending longitudinally of the foot and secured at one end to the foot body and at its other end having a loose connection to said foot-body.
- 5 10. A sewing machine presser-foot having two flat-spring bottom members extending longitudinally of the foot and each secured at one end of the foot body and at its other end having a loose connection to said foot body.
- 10 11. A sewing machine presser-foot having two flat-spring bottom members at opposite sides respectively of the bottom of the foot, said bottom members being adapted to yieldingly accommodate themselves to engagement with material of one thickness under one member and of a different thickness under the other member.
- 15 12. The combination with a presser-foot complete for ordinary use, of two flat-spring bottom member attachments adapted to yieldingly engage the work and applied to the foot to extend longitudinally thereof over opposite sides respectively of the normal work contacting bottom surface thereof.
- 20 13. As an article of manufacture, a flat-spring work contacting bottom member bowed between its ends to engage a presser-foot at both said ends and to stand away from said foot at its middle portion, said spring being adapted to be attached to a sewing machine presser-foot and yieldingly engage work passing under said foot and being bent at one end to fit over an end portion of the presser-foot.
- 25 14. A device of the class described having, in combination, a foot provided with a needle hole, and a resilient member arranged in vertical alignment with and beneath the material forming the under face of said foot, extending longitudinally thereof fast thereto at one end thereof and having its opposite longitudinally extending edges located at one side of a median vertical plane extending longitudinally of said foot and through said needle hole, whereby variations in the thickness of the work on opposite sides of said plane may be compensated for.
- 30 15. A device of the class described having, in combination, a foot and a pair of parallelly disposed resilient members arranged beneath and in vertical alignment with the material forming the under face of said foot, extending longitudinally thereof on opposite sides, respectively, and fast thereto at one end thereof and adapted to compensate for variations in the thickness of the work on opposite sides of said foot.
- 35 16. A device of the class described having, in combination, a foot and a pair of relatively movable resilient members arranged at opposite sides of said foot beneath and in vertical alignment with the material forming the under face thereof and movable toward and away from said under face adapted to compensate for variations in the thickness of the work.
- 40 17. A device of the class described having in combination, a foot, and resilient work-engaging members secured to the forward portion of said foot and extending toward the rear adjacent to the under face of said foot, said resilient members curving downwardly relatively to said under face adapted to contact therewith and to engage the work under opposite sides of said foot and to compensate for variations in the thickness of the work.
- 45 18. A device of the class described having in combination a foot provided with a needle hole, a pair of resilient work-engaging members secured to the forward portion of said foot and extending rearwardly adjacent to the under face of said foot and having slideable engagement with the rear portion of said face, said work-engaging members curving downwardly intermediate of their forward and rear ends and adapted to engage the work at points upon opposite sides of and adjacent to said hole and compensate for differences in the thickness of the work upon opposite sides of said hole.
- 50 19. A device of the class described having in combination a foot, and a pair of flat metal springs arranged adjacent to opposite sides of the under face of said foot, opposite ends of said springs engaging the front and rear portions of said foot, said springs curving downwardly away from said under face intermediate of their ends to yieldingly engage and operate work of different thicknesses.
- 55 20. A device of the class described having in combination, a foot provided with a needle hole, and a pair of work-engaging members arranged at opposite sides of said hole adjacent to the working face of said foot, said members being relatively, yieldingly movable toward and from said working face, the opposed edges of said members extending toward each other to form a relatively narrow space in front of said hole, said edges gradually receding from each other from said relatively narrow portion toward the forward portion of said foot.
- 60 21. A device of the class described having in combination, a foot and a pair of relatively resilient work-engaging members arranged side by side and extending from the forward toward the rear portion of said foot, the opposed edges of said members being formed to provide relatively wide and narrow spaces therebetween.
- 65 22. A device of the class described having, in combination, a foot provided with a needle hole and a resilient work-engaging member secured to the forward portion of said foot and extending rearwardly along opposite to

- and beneath the under face of said foot and having slidable engagement with the rear portion of said face, said work engaging member curved downwardly intermediate 70
 5 its forward and rear ends and adapted to engage the work at points at one side of and adjacent to said hole and compensate for differences in the thickness of the work upon opposite sides of said hole.
- 10 23. A device of the class described having, in combination, a foot and a flat metal spring arranged adjacent to one side of the under face of said foot, the opposite ends of said spring engaging the front and rear portions 75
 15 of said foot, with the forward end of the spring bent over and secured to the forward end of the foot, said spring curved downwardly away from said under face intermediate of its ends to yieldingly engage and 80
 20 operate upon work of different thicknesses.
24. A device of the class described having, in combination, a foot and a metal spring arranged beneath and in vertical alignment with the material forming the under face of 85
 25 said foot at one side thereof and slidably engaging the rear portion of said foot and curved downwardly away from said under face intermediate of its ends to yieldingly engage the work.
- 30 25. A device of the class described having, in combination, a foot provided with a needle hole and a work-engaging member arranged at one side of said needle hole adjacent to the working face of said foot 90
 35 and fast to the front end of said foot, said member being relatively yieldingly movable toward and from said working face, the inner edge of said member being inclined from the front end thereof at an angle 95
 40 toward the vertical median longitudinal plane of said presser foot as it approaches said needle hole.
26. A device of the class described having, in combination, a foot provided with a 100
 45 needle hole and a working-engaging member arranged at one side of said hole adjacent to the working face of said foot, said member being relatively yieldingly movable toward and from said working face, the inner edge of said member extending toward the vertical median longitudinal plane 105
 50 of said presser foot to form a relatively narrow space between it and said plane in front of said hole, said inner edge gradually receding from said median plane as it approaches the forward portion of said foot.
27. A sewing machine presser-foot having two flat-spring bottom members beneath the bottom surface of the foot and positioned 110
 60 to engage different portions of the work passing under the foot and acting to independently yieldingly engage said work.
28. A sewing machine presser-foot notched at its forward end having two flat-spring bottom members each attached to the 115
 65 foot at one end, said bottom members extending along the foot at opposite sides respectively of said notch and acting to independently yieldingly engage work thereunder. 70
29. A sewing machine presser-foot having flat-spring work contacting bottom members positioned beneath the body of the foot and to engage different portions of work passing under both of said members. 75
30. The combination of a presser-foot having a notch extending rearwardly from the front end thereof in which upstanding fabric is adapted to be advanced and trimmed before it reaches the stitch forming parts, 80
 a horizontally operating trimming mechanism including relatively movable blades cooperating at their cutting edges in said notch to trim fabric advancing therein, said presser-foot having a vertically yieldable 85
 flat-spring fabric-engaging bottom member at one side only of said notch and also having another vertically yieldable flat-spring fabric-engaging bottom member at the other side only of said notch whereby it is adapted 90
 to properly engage fabric sections of different thicknesses on opposite sides of the notch.
31. The combination of a presser-foot having a notch extending rearwardly from the front end thereof in which upstanding fabric is adapted to be advanced and trimmed before it reaches the stitch forming parts, 95
 a horizontally operating trimming mechanism including relatively movable blades 100
 cooperating at their cutting edges in said notch to trim fabric advancing therein, said presser-foot having a vertically yieldable flat-spring fabric-engaging bottom member at one side only of said notch whereby it is 105
 adapted to properly engage fabric sections of different thicknesses on opposite sides of the notch.
32. A sewing machine presser-foot having a main body and a bottom member detachably and replaceably secured to said main body and having a bottom surface for engaging the work and taking the wear of a cooperating feed member and at its opposite ends engaging around and over the edge of the body. 110
33. A sewing machine presser-foot having a main body and two bottom members each detachably and replaceably secured to said main body and having a bottom surface for 115
 engaging the work and taking the wear of a cooperating feed member and each member at its opposite ends engaging around and over the edge of the body.
34. The combination of a presser-foot having a fabric guiding slot extending rearwardly from the front end thereof and having a needle opening in rear of and in line with said slot and a trimming mechanism operating to trim fabric upstanding in and 120
 125
- 65

passing along said slot, the work engaging bottom surface of the presser-foot being constituted by two members detachably secured to the main body of the foot, the inner edges of said members being spaced apart to form a groove extending from the rear end of said slot to the needle opening and in which groove fabric is adapted to travel after being trimmed by said trimming mechanism.

35. The combination of a presser-foot having a fabric guiding slot extending rearwardly from the front end thereof and having a needle opening in rear of and in line with said slot and a trimming mechanism operating to trim fabric upstanding in and passing along said slot, the work engaging bottom surface of the presser-foot including two vertically yieldable fabric-engaging members mounted on the main body of the foot with their inner edges spaced apart to form a groove extending from the rear end of said slot to the needle opening and in which groove fabric is adapted to travel after being trimmed by said trimming mechanism.

36. The combination in a presser-foot, of a main foot body having therein a fabric guiding slot extending rearward from the front end thereof and a needle opening in rear of said slot; a trimming mechanism for trimming upstanding fabric advancing in said slot; a vertically yieldable fabric-engaging member mounted on said main foot body and having an inner inclined fabric engaging edge along a portion of said member lying under said main foot body extending from the rear end of said slot to said needle opening.

37. A presser-foot having in combination, a main foot section provided with a fabric guiding slot extending rearward from the front end thereof and a needle opening in rear of said slot; a trimming mechanism for trimming upstanding fabric advancing in said slot; a fabric-engaging member vertically yieldable with relation to said main foot section which member has an inner inclined fabric-engaging edge along a portion thereof which extends beneath said main foot section from the rear end of said slot towards said needle opening; and a vertically yieldable fabric-engaging member in rear of and in line with said needle opening.

38. In a presser-foot for sewing machines, the combination of a supporting shank; a main foot section rigid with said shank and having a bottom fabric-engaging surface; two yielding fabric-engaging members mounted on said main foot section and extending along said bottom fabric-engaging surface with their inner edges spaced apart the space between said edges constituting a channel in which fabric travels and is guided in its passage along the presser-foot.

39. In a presser-foot, the combination of

a main foot body having a fabric-guiding slot extending rearwardly from the front end thereof and having a needle opening in rear of said slot; a trimming mechanism operating to trim fabric upstanding in and passing along said slot; and two vertically yieldable fabric-engaging members mounted on and extending beneath said main foot body and having their inner edges relatively near together in advance of said needle opening and offset away from each other at said opening.

40. In a presser-foot, the combination of a main foot body having a fabric-guiding slot extending rearwardly from the front end thereof and having a needle opening in rear of said slot; a trimming mechanism operating to trim fabric upstanding in and passing along said slot; and two vertically yieldable flat spring fabric-engaging members mounted on and extending beneath said main foot body and having their inner edges relatively near together in advance of said needle opening and offset away from each other at said opening.

41. In a presser-foot, the combination of a main foot body having a needle opening; and two vertically yieldable fabric-engaging members mounted on and extending beneath said main foot body with their inner edges relatively near together in advance of said needle opening and offset away from each other at said opening.

42. In a presser-foot, the combination of a main foot body having a fabric-guiding slot extending rearwardly from the front end thereof and having a needle opening in rear of said slot; a trimming mechanism operating to trim fabric upstanding in and passing along said slot; and a vertically yieldable fabric-engaging member mounted on and extending beneath said main foot body and having its inner edge offset in advance of said needle opening.

43. In a presser-foot, the combination of a main foot body having a fabric-guiding slot extending rearwardly from the front end thereof and having a needle opening in rear of said slot; a trimming mechanism operating to trim fabric upstanding in and passing along said slot; and a vertically yieldable flat spring fabric-engaging member mounted on and extending beneath said main foot body and having its inner edge offset in advance of said needle opening.

44. In a presser-foot, the combination with a main foot body having a needle opening and a bottom surface portion adapted to engage downwardly upon the fabric; and a vertically yieldable fabric engaging member mounted on and extending beneath said main foot body along said fabric-engaging bottom surface portion thereof and having its inner edge offset in advance of said needle opening.

45. As an article of manufacture, a flat-
spring work contacting bottom member
bowed between its ends to engage a presser-
foot at both ends and to stand away from said
foot at its middle portion, said spring being
adapted to be attached to a sewing machine
presser-foot and yieldingly engage work
passing under said foot and being bent at
both ends to fit over end portions of the
presser-foot.

10 In testimony whereof we have signed this
specification.
